UNITED STATES PATENT OFFICE.

W. H. PEASE, OF DAYTON, OHIO.

IMPROVED WARDROBE-BEDSTEAD.

Specification forming part of Letters Patent No. 40,184, dated October 6, 1863.

To all whom it may concern:

Be it known that I, W. H. PEASE, of the city of Dayton, and State of Ohio, have invented certain new and useful Improvements in Wardrobe-Bedsteads; and I hereby declare that the following is a true and exact description of the same, reference being had to the accompanying drawings, and to the letters of reference marked thereon.

Figure 1 in the annexed drawings represents a vertical section of the press and bedstead contained within it. Fig. 2 represents a plan view of the bedstead when withdrawn from the wardrobe and lying in a horizontal position.

The letter A in Fig. 1 represents the press, which is adapted in size to the bedstead designed to occupy it. The press A is furnished with two sets of folding doors, one set being hinged to each of the sides of press A in front. When the bedstead is to be withdrawn from the wardrobe, the doors are thrown back, as seen in Fig. 2, letter e. When the bedstead is returned to the press, the doors are swung around and meet at a point midway between the sides of press A, and confine the bedstead B securely in its upright position.

The bedstead B consists of the two side rails, f, the head and foot pieces a, and the cross-ties g and h. Near the tie g, and on a level with it, is the broad slat or board b, which is secured to tie g by means of two iron screws, (marked d). Extending from board b to cross-tie h are the flexible slats or cords o o, intended as a support of the bed.

In order to keep the bed snugly in position when within the wardrobe, the slats c c are

provided, and are made to extend lengthwise of bedstead B. The opposite ends of slats c have a screw inserted on the upper surface of each, the heads of these screws being designed to enter a slit in the leather straps I, the straps I being nailed inside of head and foot pieces a.

P represents a sand-box resting on the tie g, and intended as a counterpoise to that portion of the bedstead B which, when in a horizontal position, is outside of the press A.

The bedstead B is made to play upon a fulcrum consisting of two iron bolts or pivots, which penetrate the opposite rails of the bedstead and enter the sides of press A. The foot of bedstead B is suspended on its pivots so near the back of press A as barely to admit B playing freely when raised or lowered. When the bedstead B is in a horizontal position, the slats c are unlooped from the straps I and placed in an upright position within the wardrobe A.

m represents the legs of the bedstead B, and are hinged to its outer end and made to fold back against the head-board a.

Having thus described my wardrobe-bedstead, what I claim, and desire to secure by Letters Patent, is—

The arrangement of the sand box or weight P, the adjustable board b, the screws d d, and the cords or flexible slats c c, in the manner and for the purpose herein set forth.

W. H. PEASE.
